PORTABLE DRINKING FOUNTAIN

John R. Hunneman, Woburn, Mass.

Application April 14, 1937, Serial No. 136,741

1 Claim. (Cl. 299—17)

My present invention is a novel and improved portable drinking fountain designed particularly for cooperation with a water faucet of any size or style.

5 An important object of the invention is to improve and perfect the type of drinking fountain illustrated, described, and claimed in my prior and copending application on Faucet drinking attachment, Ser. No. 132,982, filed March 25, 1937.

10 In my present development of fountain drinking device for cooperation with or attachment to the usual type of water faucet in kitchens, bathrooms, or lavatories I have discovered and devised an extremely efficient liquid conducting conduit, together with means to attach the same to or hold said conduit in operative or inoperative position with the delivery opening of the faucet with which it is used, whereby a proportional part of the liquid flowing from the faucet may be 20 deferred into fountain drinking position; and, furthermore, my invention enables the use of the conduit with every faucet irrespective of size because of this proportional feature, whereby the conduit does not have to be of the same dimensions, diameter, or contour as that of the faucet with which it is used.

In my present development of this drinking fountain device I provide a portable drinking fountain attachment which can be instantly applied to and preferably register with the delivery portion of a faucet and held in position to operate as a drinking fountain, and thereupon removed and carried by the operator in his pocket or hung on a hook or support adjacent the 35 faucet.

This improved portable attachable and detachable fountain drinking device is, furthermore, suitable for use where the water faucets, as in some wash basins or lavatories, are extremely 40 close to the edge of the basins. Also the device is equally applicable whether the faucet with which it is desired to be used as a drinking fountain attachment is either at the right or left side of the basin.

45 Simple means for holding and supporting the portable drinking fountain are provided and consist preferably of a projecting stem or handle with holding means at the end opposite to the conduit.

50 As shown in the drawing illustrating a preferred embodiment of the present invention,

Fig. 1 is a perspective view of my improved portable drinking fountain attachment and holding means;

55 Fig. 2 is a diagrammatic plan view illustrating

the holding of the drinking fountain attachment by the operator in position under the delivery end of the faucet;

Fig. 3 is a cross-sectional view on the line 3—3 of Fig. 2 illustrating the fountain in use.

Fig. 4 is a diagrammatic view illustrating the capacity of the fountain to cooperate with either a right- or left-hand faucet, and

Fig. 5 is a diagrammatic view illustrating a use of my portable drinking fountain attachment 10 with a typical movable faucet showing capacity for cooperative use of the attachment in any position to which the movable faucet is employed.

Referring to the drawing, I illustrates a typical form of my liquid conducting conduit wherein the 15 same is substantially in the form of a semi-circular section of a tubing, having openings 2—2, either of which may be the receiving or delivery opening, the openings 2—2 being spaced apart or otherwise constructed to provide a central recess 20 3, which is of suitable size to register with the usual rim 5 of a water faucet 6 so that the conduit I may thus hold steadily in cooperative position with the faucet by positioning the conduit against the rim 5. Any suitable holding means 25 is provided, that as herein shown being a wire handle 18 secured to the conduit I at one end, and having at the opposite end a curved portion 12 for better holding by the operator when positioning the portable drinking fountain under the 30 rim of the faucet, as illustrated diagrammatically in Fig. 2.

The recess 3 enables the drinking fountain to be fitted to and steadied thereby at any position on the rim 5 around the delivery opening of the 35 faucet 6.

It is immaterial whether or not the recess 3 between the openings 2—2 in the conduit I correctly fits the rim 5 or not since this will, nevertheless, enable the conduit I to be applied to and 40 steadied on the delivery opening of the faucet during its use.

I find that a semi-circular conduit is quite efficient for this portable drinking fountain device, enabling either end to be utilized as the 45 receiving or delivery end, although I may if desired utilize a special form of conduit, such for example as shown in my said copending application Ser. No. 132,982, wherein the receiving end is somewhat larger than the delivery mouth 50 or opening to produce a slight nozzle-like effect to project the liquid at a greater distance and to have the same more compact in the delivery path of flow. Either form, or others, may be equally applicable, the present semi-circular type being 55

found properly efficient and effective, substantially as illustrated in Fig. 3.

In Fig. 4 I have shown a typical washbasin 15, having a right-hand faucet 16 and left-hand faucet 17, with the delivery spout or portion 6 overhanging the edge 18 of the basin very closely, leaving but scant room for any attachment, as is sometimes the installation employed. However, with my portable drinking fountain device I can 10 position the same for cooperative use even with such installations, and at either the right or left as indicated in full line position at the right-hand faucet 16, or in the dotted line position at the left-hand faucet 17.

In Fig. 5 I have illustrated a modified form of 15 kitchen sink or laundry tub 20, having a fixture comprising the two faucets 21 and 22 for hot and cold water, with the connecting fixture 23 and a movable spout or faucet 25 cooperating 20 therewith and adapted to swing from one side to the other for delivery into the basin 26 or 27, as desired. Such movable faucet 26, irrespective of

its position, can be instantly utilized with my portable drinking fountain, as clearly shown in both full and dotted line position, and as will be readily understood.

I claim:

A portable sanitary drinking device of the kind described, comprising a substantially semi-circular conduit to utilize a liquid flow of water in one direction, and direct the same therefrom upwardly as a drinking fountain, said curved conduit having the inner curved surface of suitable size to fit, automatically and adjustably, the rim portion of a faucet, pipe, or the like from which liquid flows, in combination with an extending handle secured to the conduit intermediate the 15 receiving and delivery openings, and extending substantially at a right angle to the line of flow thru said conduit, said delivery and receiving openings being equal to permit interchangeable use of either as the liquid-receiving and fountain- 20 delivery portions.

JOHN R. HUNNEMAN.
